DISCHARGE TUBE COMPRISING A METAL ENVELOPE AND FOR USE AT VERY SHORT WAVE-LENGTHS

Eduard Gerhardus Dorgelo, Eindhoven, Netherlands, assignor to Hartford National Bank and Trust Company, Hartford, Conn., as trustee

Application July 8, 1952, Serial No. 297,681

Claims priority, application Netherlands
July 17, 1951

1 Claim. (Cl. 313—318)

1 This invention relates to discharge tubes comprising a metal envelope and for use at very short wavelengths. A proposed tube comprises a glass protective hood surrounding one or more lead-in wires led through the envelope with the use of glass intermediate pieces, the lead in wires being connected by substantially flexible conductors to connecting contacts on the protective hood. This hood, which is shaped in the form of a truncated cone having a generally oval-shaped section is for protecting the fragile seals from mechanical damage.

It has been found that, particularly if pulsatory voltage differences having a steep front occur between the lead-in wire and the metal tube envelope, sparking may occur from the lead-in wires to the lateral walls of the glass protective hood. This sparking may occasion fusing of the lead-in wires and losses and disturbance in the operation of the tube.

According to the invention, a metal discharge tube comprising a metal envelope and for use at very short wave-lengths in which a glass protective hood surrounds one or more lead-in wires led through the envelope of the tube and connected by substantially flexible conductors to supply contacts on the protective hood, is characterized in that a conductor shaped in the form of a small spring is arranged between each lead-in wire and the inner surface of the side of the protective hood so as to be in mechanical contact therewith.

The incidence of sparking and arcing to the protective hood is thus at least reduced even in the case of steep-fronted voltage differences

2 between the lead-in wire and the metal tube envelope.

The invention will now be described with reference to the accompanying diagrammatic drawing, given by way of example, in which

Figs. 1 and 2 are sectional views at right angles of a discharge tube according to the invention.

Referring now to the figures, 1 designates the metal tube envelope, 2 an oval-shaped protective hood of hard glass, 3 designates two incandescent cathode lead-in wires led through the envelope 1 with the use of glass intermediate pieces 4. Substantially flexible conductors 5 provide connection to supply contacts 6 in the flat upper part 7 of the protective hood 2. Each of the wires 3 has secured to it a small metal spring 8 which makes mechanical contact with the protective hood 2. The cooling fins of the metal tube are designated 9.

20 What I claim is:

An electric discharge adapted to be operated at very short wave-lengths comprising a metal envelope, a plurality of lead-in conductors extending into said envelope, a glass protective hood surrounding said lead-in conductors, supply contacts on the hood, a plurality of flexible conductors each connecting one of the lead-in conductors to one of said contacts, and a leaf-spring conductor element interposed between each lead-in conductor and the inner surface of said hood and in mechanical contact therewith.
